UNITED STATES PATENT OFFICE.

ROBERT H. KUSS, OF CHICAGO, ILLINOIS, ASSIGNOR TO K-R FURNACE COMPANY, A CORPORATION OF ILLINOIS.

FURNACE-GRADE CONSTRUCTION.

Application filed May 12, 1921. Serial No. 468,927.

To all whom it may concern:

Be it known that I, ROBERT H. KUSS, a citizen of the United States, and a resident of Chicago, Cook County, State of Illinois, have invented a certain new and useful Improvement in Furnace-Grate Construction, of which the following is a specification.

This invention relates to furnace grates in general, but more particularly to those in which the grate is inclined to feed the burning and coking fuel downward toward the bridge wall, and which have a hopper for feeding the coal to the upper portion of the grate.

Generally stated, the object of the invention is to provide a novel and approved construction whereby the feeding of the coal from the hopper to the grate is facilitated by certain improvements hereinafter described, and whereby the burning and coking fuel is caused to slide downward on the grate, from time to time, by reason of certain improvements which make it possible to give the grate, or certain portions thereof, a shaking motion which not only causes the burning and coking fuel to slide downward toward the bridge wall, but which also tends to release the coal from the hopper onto the upper portion of the grate, as will hereinafter more fully appear.

It is also an object to provide certain details and features of construction and combinations tending to increase the general efficiency and the desirability of a furnace grate of this particular construction.

To these and other useful ends the invention consists in matters hereinafter set forth and claimed, and shown in the accompanying drawings in which—

Figure 1 is a longitudinal section of a furnace grate embodying the principles of the invention, being a section on line 1—1 in Figure 3, looking in the direction indicated by the arrows.

Figure 2 is a similar view, being a section on line 2—2 in Figure 3, looking in the direction of the arrows.

Figure 3 is a front elevation of said grate, with some of the things in the background omitted.

Figure 4 is a plan of said grate, certain

transverse supporting members beneath the grate not being shown.

Figure 5 is a detail sectional view.

Figure 6 is a detail section on line 6—6 in Figure 1.

Figure 7 is a section on line 7—7 in Figure 1.

Figure 8 is a detail section on line 8—8 in Figure 1.

As thus illustrated, the invention comprises a front frame 1 forming the stationary structure at the front of the furnace and provided at a suitable height with an inclined plate 2 which, in conjunction with the inner vertical plate 3, forms a hopper for feeding the coal downward to the grate. The bridge wall 4 is of any suitable known or approved character. Inclined stationary frames 5 and 6 have their upper ends bolted at 7 to the main frame 1, being interlocked with the latter at 8, and the lower ends of these frames are secured by bolts 9 to the masonry in front of said bridge wall.

The upper section 10 of the grate is parallel with the plate 2, in normal position, and is mounted to rock about a transverse axis 11, and is spaced a distance from the lower edge of the plate 2, whereby an opening 12 is formed through which a poker can be inserted to facilitate the feeding of the coal from the hopper to the grate. The inclined stationary grate bars 13 are suitably mounted on the transverse members 14 and 15, which members are in turn bolted to the stationary frames of the grate structure. The

movable grate bars 16 alternate with the stationary grate bars, being shorter at each end than the stationary bars, as shown and are supported by pivot rods 17 on the upper ends of the arms 18 of the two rock shafts 19 and 20, which latter have downwardly extending arms 21 which are connected by links 22 and 23 to the triangular pivoted member 24 at the front of the furnace, and by means of a handle 25 applied to the pivoted member 24 the rock shafts 19 and 20 can be rocked with the result that the bars 16 will be moved up and down, thus lifting the fuel and ashes and, in effect, shaking the grate to produce the desired results. The arms 18 are of the same length and have the

same angle, relatively to the grate, so that the angle of inclination of the bars 16 is maintained. The section 10 is composed of a plurality of plates 26 arranged side by side on the axis 11, and each plate has a plurality of long and short portions 27 to rest on the member 14, the relatively short portions being opposite the bars 13, while the relatively long portions extend between these bars 13, whereby the plates 26 form an inclined receiving and coking ledge for delivering the coal to the inclined grate, in a manner that will be readily understood. Lugs 28 on the plates 26 engage the lugs 29 on the member 14 to limit the tilting motion of these plates forming said ledge below the hopper. Each plate has an opening 30 through which a handle or bar can be inserted into the recess 31 to rock the plate about its axis, and thus each plate can be rocked separately without disturbing the others when it is desired to feed the coal downward from the hopper. Of course, in a grate structure of this character, the raising and lowering of the bars 16 not only causes the burning fuel to slide downward on the grate, and the ashes to drop through into the ash pit below, but tends also to release the coal from the hopper, as any disturbance on the grate which causes the burning and coking fuel to slide downward thereon will tend to release more fuel from the hopper; but, in order to facilitate the feeding of the fuel from the hopper, the plates 26 are rocked in the manner described, and if necessary a poker can be inserted through the opening 12 to push the fuel immediately below the hopper and thus facilitate the feeding thereof to the grate.

The end, or horizontal grate section 32 is of any suitable character, and is mounted on the frames 5 and 6 to rock about the transverse axis formed by the trunnions 33 and this grate section is connected by a rod or link 34 with the bell-crank 35 pivoted at 36 on the front stationary structure of the furnace grate. The said trunnions are all fully covered, it will be seen, so that they are protected against ashes and clinkers and fuel. A handle 37 applied to said bell crank provides the means for rocking the grate section 32 about its axis 33 in a manner to dump the ashes and exhausted fuel into the pit in front of the bridge wall. The narrow section 38 is interposed between the two large sections of the grate 32 to cover the joint between the two large sections, as well as the center bearings for the two middle trunnions 33 forming said axis. The bell crank 35 has a lug 39 which normally rests upon the horizontal upper end portion of the pin 40 which is rotatably supported in the lug 41 on the main stationary frame of the furnace. By turning the pin 40 to release its head from the lug 39, the handle 37 can

then be pulled outward, with the result that the rod 34 will tilt the section 32 of the grate.

The bars 13 have end notches 42 to engage the members 14 and 15, and a key 43 is inserted between the member 15 and the end of said bars to lock them against downward displacement. By removing this key, the bars may be moved downward endwise, the notch 42 that engages the frame element 15 being long enough to permit this downward displacement of the bars, and this will disengage their upper ends from the member 14, so that any bar can be removed. Lugs 44 on the member 15 serve to space the bars 13 apart the required distance.

As shown in Figure 8, the rock shaft 20 has end portions 45 which are supported in suitable bearings on the frame. By removing the bolts 46 inserted through said bearings at the outer sides of the frame, the shaft 20 can be lifted out of the structure. Similar means, it will be understood, are provided for supporting the shaft 19 on the frame. The rods 17 are removable to permit the bars 16 to be removed when necessary or desirable, and when this is done any bar 16 can be removed individually without the necessity of removing any other bar from the furnace.

It will be seen that the rocking members 24 and 35 are provided in duplicate, one for each side of the grate structure, so that either the right hand portion of the grate or the left hand portion thereof can be shaken independently, without shaking the other portion, as will be readily understood.

The pin 47 is preferably provided to lock the triangle 24 in normal position, thus holding the bars 16 in normal position, as shown. When this pin is removed the bars 16 can then be raised above the stationary bars 13, and then lowered below the same, so that in shaking the grate, or in doing what is equivalent in a general way to shaking the grate structure, the movable bars 16 rise and fall above and below the top surface of the stationary bars. This allows the ashes to fall down between the bars, but does not disturb the fuel bed in a manner to mix the ashes and clinkers with the burning fuel. The shearing action between the bars tends to keep the air spaces clear of clinkers, and it will be seen that this shearing action is in both directions, up as well as down, as the movable bars move below the stationary bars, as well as above the latter. The upward movement of the movable bars is substantially in a direction at right angles to the plane of the grate, so that the fuel moves rearward as well as upward.

As a matter of further and special improvement, the plate 2 may be adjustable in the plane thereof, by edgewise sliding displacement on the supports 48, to vary the

size of the hopper feed opening. Of course, this adjustment can be accomplished in various ways, for this purpose, as the object to be attained is the regulation of the feeding 5 action for fuel of different kinds.

Thus it will be seen that the stationary bars 13 are arranged in groups, with the upper ends of each group separate, but with their lower ends united by the portions 49 10 shown more clearly in Fig. 4 of the drawings. There are three bars in each group, it will be seen, except the center group, in which latter there are five bars connected together at their lower ends by the portion 50, 15 and in this group the bars do not alternate with movable bars. In the groups having their lower ends united by the portions 49, the upper ends of such bars alternate with the long bar portions 27 previously 20 described. Thus the short and long portions 27 form part of the grate structure, and are integral with the plates 10 which are smooth and flat to receive the fuel from the hopper, and which feed the fresh fuel to the grate 25 structure below.

Without disclaiming anything, and without prejudice to any novelty disclosed, what I claim as my invention is:—

1. In a furnace grate, the combination of 30 stationary inclined bars arranged in groups, with the bars of each group united at their lower ends but separated at their upper ends, movable inclined bars alternating with the stationary bars, the stationary bars extending beyond the upper and lower ends of 35 the movable bars, and mechanism to operate said movable bars and to raise and lower them a distance to move the fuel on the grate.

2. A structure as specified in claim 1, said bars being all so inclined at the same angle that the motion of the movable bars causes the fuel to move downward on the grate.

3. A structure as specified in claim 1, said 45 movable bars having movement bodily in a rearward direction as well as upward, and a bridge wall toward which the fuel is caused to move by the shaking of the grate.

4. A structure as specified in claim 1, said 50 mechanism comprising rock shafts provided with arms upon which the movable bars are pivoted and means to rock the shafts about parallel transverse axes of motion therefor.

5. A structure as specified in claim 1, said 55 movable bars being structurally separate from each other and removable from between said stationary bars.

6. A structure as specified in claim 1, in 60 combination with a hopper to feed the fuel to said grate, and a frame to support the entire grate in an inclined position to feed the fuel downward thereon from said hopper.

7. In a furnace grate, the combination of 65 a hopper, an inclined grate structure, and oscillatory means comprising smooth flat in-

clined plates below said hopper and having their lower edges formed with projections extending into and forming a part of the upper portion of said grate structure, movable about a transverse axis to feed the fuel 70 from said hopper to the upper end of the grate.

8. A structure as specified in claim 7, said oscillatory means being mounted to tilt about the transverse axis to lift and stir the green 75 fuel on the upper end portion of said inclined grate.

9. A structure as specified in claim 7, said oscillatory means comprising means whereby each plate may be tilted without disturbing 80 the others, and means to limit the tilt of said plates both up and down.

10. A structure as specified in claim 7, there being space between said hopper and the upper edge of said oscillatory means to 85 provide an opening through which a poker can be inserted to stir the fuel.

11. A structure as specified in claim 7, said grate structure having provisions to limit the up and down tilting motion of the 90 lower edge of said oscillating means.

12. In a furnace grate, the combination of 95 a frame, stationary removable grate bars arranged in groups, with the bars of each group united at their lower ends but separated at their upper ends, having end notches to engage said frame, so that any group can be removed by downward end-wise displacement thereof sufficient to disengage the upper end thereof, means engaging the lower ends of said bars to lock them against such displacement until the removal of any group is desired, and movable bars alternating with the stationary bars.

13. In a furnace grate, the combination of 100 an inclined grate, and a hopper having a feed opening for feeding the coal to the upper end of the grate, said hopper having an inclined front plate which is movable edge-wise in the plane thereof, substantially parallel with the upper portion of the grate to in effect change or vary the size of the hopper feed opening for different kinds of fuel, a tilting inclined member immediately below the hopper to receive the fuel, with space 105 between the upper edge of said member and the lower edge of said plate, which space is variable by the tilting of said member, said member being disposed in position to feed the fuel to the upper end of said grate.

14. In a furnace grate, a set of relatively 110 long stationary grate bars arranged in groups, with the bars of each group united at one end and separated at the other end, means extending between the separated ends to cooperate therewith to support the fuel, a set of relatively short movable grate bars 115 alternating with the stationary bars, and instrumentalities for moving the movable bars a distance above the stationary bars, and 120 125 130

also a distance below the tops of the latter, so that the fuel is raised and lowered on the grate.

15. A structure as specified in claim 14, in combination with means for supporting said grate in an inclined position, with said bars thereof extending longitudinally of the grate structure, and said instrumentalities causing said movable bars to move upward and downward in a direction at an angle to the inclined plane of the grate, so that the fuel is moved rearward as well as upward.

16. A structure as specified in claim 14, in combination with means for locking said instrumentalities against movement, so that the stationary and movable bars are normally in the same plane.

17. A structure as specified in claim 14, said instrumentalities being adapted to move said movable bars up and down bodily in a direction at right angles to the plane of the grate.

ROBERT H. KUSS.
